UNITED STATES PATENT OFFICE.

WILLIAM C. RASTETTER, OF FORT WAYNE, INDIANA.

TENNIS-RACKET FRAME.

Application filed September 24, 1924. Serial No. 739,547.

This invention relates to improvements in tennis racket frames, and the object thereof is to afford a racket frame of such structure as to withstand extreme strains to which racket frames are subjected, especially at the juncture of the loop of the frame and the handle with which it is connected.

This object is accomplished by the construction illustrated in the accompanying drawings, in which:

Fig. 1 is a fragmentary front elevation of a structure embodying the invention; and

Fig. 2 is a section of Fig. 1 on the line 15 2—2 thereof.

The characters appearing in the description refer to parts shown in the drawings and designated thereon by corresponding characters.

20 The invention comprises an oval frame 1 formed of a wooden strip 1, preferably made up of laminæ 2, 3, 4, 5 and 6 and an outer lamina 7 of vulcanized fiber or similar material. The strip, however, may be of a 25 single piece of wood. The ends of the strip are united with a heart 8 interposed therebetween at the juncture of the loop formed by the strip and the handle 9.

Extending over the top of the heart and 30 upon the adjacent inner faces of the strip is superimposed a shoe 10 preferably made up of wooden or other fibrous laminæ.

An especial feature of the invention consists of a longitudinally tapering wedge 11 35 made up of wooden laminæ 12, the grain of the several laminæ extending relatively in different directions. This wedge is introduced into the frame structure midway between its front and back faces 13 and 14 40 in a kerf made in the frame for its reception, the front and back of the frame being spread apart to accommodate the wedge. In this manner an increasing thickness 45 commencing in the lower portion of the loop and extending into the handle is established in the frame with correspondingly increased strength. The

wedge extends laterally through the corresponding sides of the strip and also through the heart and the shoe, with all of which 50 it is securely joined by means of glue. The structure thus set forth affords a frame of great rigidity and strength, especially at the juncture of the loop and handle where the strains occasioned by usage are greatest. 55

What I claim is:—

1. A tennis racket frame structure including a loop and contiguous handle and an interposed heart at the juncture of the loop and handle; a superimposed shoe extending over the top of the heart and the inner faces of the loop adjacent thereto; and a longitudinally tapering wedge interposed in the frame midway between its front and back and extending from a point in the 60 lower part of the loop into the handle and through the shoe and heart.

2. A tennis racket frame structure including a loop and contiguous handle and a heart interposed at the juncture of the loop and handle; and a longitudinally tapering reinforcement interposed in the frame at the juncture of the loop and handle and extending through the heart in a plane midway between the front and back of the 70 frame.

3. In a tennis racket frame structure including a loop and contiguous handle formed of a bent strip of wood and a heart interposed between the end portions of the 80 strip at the juncture of the loop and handle, there being a kerf made in the frame midway between its front and back in a plane parallel therewith and extending through the juncture and partly into the loop; and a longitudinally tapering wedge fixed permanently in the kerf and spreading the adjacent front and back portions of the frame 85 outwardly from their normal planes. 90

In testimony whereof I affix my signature.

WILLIAM C. RASTETTER.
